UNITED STATES PATENT OFFICE.

WALTER L. FORWARD, OF BERKELEY, CALIFORNIA.

DESIGN FOR A DIFFUSION-DISK.

45,335.

Specification for Design.

Patented Mar. 3, 1914.

Application filed January 21, 1913. Serial No. 743,414. Term of patent 14 years.

To all whom it may concern:

Be it known that I, WALTER L. FORWARD, a citizen of the United States, residing at Berkeley, in the county of Alameda and State of California, have invented a new, original, and ornamental Design for a Diffusion-Disk, of which the following is a specification, reference being had to the accompanying drawings, forming part thereof. Figure 1 is a view of the obverse side of

the diffusion disk. Fig. 2 is a view of the reverse side of the disk. Fig. 3 is an edge elevation of the invention.

I claim:

The ornamental design for a diffusion disk, as shown.

WALTER L. FORWARD.
